UNITED STATES PATENT OFFICE.

SAMUEL G. CABELL, OF WASHINGTON, DISTRICT OF COLUMBIA, ASSIGNOR,
BY DIRECT AND MESNE ASSIGNMENTS, TO THE LIQUID PURIFYING
COMPANY, OF WEST VIRGINIA.

APPARATUS FOR PURIFYING AND AGING LIQUORS.

SPECIFICATION forming part of Letters Patent No. 404,682, dated June 4, 1889.

Application filed No. 5, 1888. Serial No. 272,921. (No model.)

To all whom it may concern:

Be it known that I, SAMUEL G. CABELL, a citizen of the United States, residing at Washington, in the District of Columbia, have invented certain new and useful Improvements in Apparatus for Purifying and Aging Liquors; and I do hereby declare the following to be a full, clear, and exact description of the invention, such as will enable others skilled in the art to which it appertains to make and use the same.

My invention relates to improvements in apparatus for purifying, changing, deodorizing, and modifying the condition and properties or characteristics of fluids, such as water, mineral and other oils and their distillates, distilled and fermented liquors, and other analogous liquids which are subject to the catalytic or other effects of magnetism.

The invention consists, essentially, in an electro-magnetic tube or series of magnetic tubes joined together to form a conduit for the passage of liquids by gravity or otherwise from a source of supply to a proper receptacle.

The invention also consists in a magnetic conduit consisting of a plurality of legs extending upward from a given plane.

It also consists in the combination, with a magnetic conduit, of foraminated magnetic diaphragms, and in the combination, with the magnetic conduit, of sediment drums or receptacles, and in other details enumerated in the claims hereto appended.

In the drawings forming a part of this specification, Figure 1 is a side elevation, partly in section, of an apparatus made according to my invention. Fig. 2 is a plan of the same. Fig. 3 is an inverted or bottom plan. Fig. 4 is an end elevation, the top being partly broken away. Fig. 5 is a plan of a diaphragm to be inserted at intervals in the conduit, and Fig. 6 is a sectional detail.

A is the base or support. B B are sections of an iron or steel pipe or conduit, firmly attached to said support. This conduit consists, by preference, of a plurality of vertical legs connected together by return-couplings, as shown.

The entire length of the conduit may be

inclosed by a coil or helix of insulated wire 50, to constitute a single hollow electro-magnet, or each leg may separately constitute a hollow magnet; or, as I prefer and have illustrated, the legs are connected at the bottom in magnetic pairs by the return-coupling b, of iron 55 or steel, and the pairs of legs are connected at the top by return couplings b', of rubber, tin, copper, or other non-magnetic material.

For trapping and removing the sedimentary or other impurities, I attach a drum or receptacle C to the bottom coupling. These receptacles may be of any suitable form, and are by preference transparent, so that the results of the process may be observed.

Petcocks c are provided for drawing off the 65 deposits in the drums and for flushing the same. Air-domes c' are attached to the couplings at the top.

At intervals along the conduit I place 70 laminated diaphragms d d, (shown in elevation at Fig. 5,) for breaking up and separating the particles of liquid, so that all parts may pass within the influence of the field of the greatest force. These diaphragms may have any character of openings best adapted 75 to break up the current in the conduit, and may be situated at any desired points along the channel; but for convenience of adjustment I have placed them at the joints between the pipe-sections and the couplings, as 80 indicated in the drawings. I have shown the conduit as provided with a funnel d' at one end and a nozzle d² at the other; but obviously it may be coupled in any suitable way 85 with a source of supply and a storing-receptacle.

It should be understood that the stand or base with which this conduit is connected is no part of my invention, nor is the form or character of any of the parts separately any 90 part of said invention, the essential features of the invention being a magnetic tube or passage for liquids, whereby they flow or pass through and across a powerful magnetic field. The practical way of making this conduit is 95 to couple the pairs of legs at the bottom and surround them with spools in the ordinary way of making electro-magnets, couple the

pairs of legs at the top, and then connect the wires of the spools together and with a source of electricity. Water is rendered clear and the impurities thereof are destroyed and removed, petroleum distillates are deodorized or rendered inoffensive, and fresh or recently distilled spirits, wine, and other alcoholic liquors are cleaned, improved, and transformed to a condition such as they would acquire from great age by merely passing through my electro-magnetic tube or conduit. Having now described my invention, what I claim as new, and desire to secure by Letters Patent, is--

15 1. In a liquid-purifier, the combination of a plurality of vertically-arranged hollow cores or legs connected together by return-couplings and corresponding electro-magnetic coils around said cores, substantially as described.

20 2. In a liquid-purifier, a conduit consisting of a series of tubular sections of magnetic material and an electro-magnetic helix surrounding said sections, the same being connected at the top by non-magnetic material and at the bottom by magnetic material, substantially as described.

25 3. In a liquid-purifier, the combination of a hollow core of magnetic material serving as a

conduit for the passage of liquid, interposed foraminated diaphragms, and an electro-magnetic helix or coil around said core, substantially as described.

4. In a liquid-purifier, an electro-magnetic conduit having a plurality of coupled tubes and foraminated diaphragms at the joints of the coupling, substantially as described.

5. In a magnetic purifier, the combination of a series of tubes of magnetic material arranged in pairs, which are connected magnetically at their lower ends and non-magnetically at their upper ends, and a series of electro-magnetic helices corresponding with the cores or tubes, substantially as and for the purposes specified.

6. The combination, with a series of electro-magnetic tubes, of a sediment drum or receptacle located below and connected with said tubes, substantially as and for the purposes specified.

In testimony whereof I affix my signature in presence of two witnesses.

SAMUEL G. CABELL.
